US0D1084262S

(12) **United States Design Patent** (10) Patent No.: **US D1,084,262 S**
(45) Date of Patent: ** Jul. 15, 2025

(54) **AIR CONDITIONER**

(71) Applicant: **GD MIDEA AIR-CONDITIONING EQUIPMENT CO., LTD.**, Foshan (CN)

(72) Inventors: **Haiyan Zhong**, Guangdong (CN); **Yingkun Cui**, Guangdong (CN); **Lin Gan**, Guangdong (CN); **Jiabing Ye**, Guangdong (CN); **Hyunmin Ham**, Guangdong (CN); **Yongyi Yang**, Guangdong (CN); **Lilong Zhou**, Guangdong (CN)

(73) Assignee: **GD MIDEA AIRCONDITIONING EQUIPMENT CO., LTD.**, Guangdong (CN)

(**) Term: **15 Years**

(21) Appl. No.: **35/518,304**

(22) Filed: **Sep. 13, 2022**

(80) **Hague Agreement Data**

Int. Filing Date: **Sep. 13, 2022**
Int. Reg. No.: **DM/223495**
Int. Reg. Date: **Sep. 13, 2022**
Int. Reg. Pub. Date: **Sep. 15, 2023**

(30) **Foreign Application Priority Data**

Apr. 6, 2022 (CN) 202230187810.8
Apr. 12, 2022 (CN) 202230201460.6
Apr. 12, 2022 (CN) 202230201471.4

(51) **LOC (15) Cl.** **23-04**

(52) **U.S. Cl.**

USPC **D23/351**

(57) **CLAIM**

The ornamental design for an air conditioner as shown and described.

DESCRIPTION

1. Air conditioner
2. Air conditioner
3. Air conditioner
4. Air conditioner
5. Air conditioner
6. Air conditioner
- 1.1: Perspective
- 1.2: Front
- 1.3: Back
- 1.4: Left
- 1.5: Right
- 1.6: Top
- 1.7: Bottom
- 2.1: Perspective
- 2.2: Front
- 2.3: Back
- 2.4: Left
- 2.5: Right
- 2.6: Top
- 2.7: Bottom
- 3.1: Perspective
- 3.2: Front
- 3.3: Back
- 3.4: Left
- 3.5: Right
- 3.6: Top

(Continued)

3.7: Bottom**4.1:** Perspective**4.2:** Front**4.3:** Back**4.4:** Left**4.5:** Right**4.6:** Top**4.7:** Bottom**5.1:** Perspective**5.2:** Front**5.3:** Back**5.4:** Left**5.5:** Right**5.6:** Top**5.7:** Bottom**6.1:** Perspective**6.2:** Front**6.3:** Back**6.4:** Left**6.5:** Right**6.6:** Top**6.7:** Bottom

FIG. 1.1 to FIG. 1.7, FIG. 2.1 to FIG. 2.7, FIG. 3.1 to FIG. 3.7, FIG. 4.1 to FIG. 4.7, FIG. 5.1 to FIG. 5.7, and FIG. 6.1 to FIG. 6.7 show an air conditioner according to different

embodiments of the present design. Broken lines form no part of the claimed design.

1 Claim, 42 Drawing Sheets
